INVENTOR:
WILLIAM MANDEL
BY Whitley and Ruckman
ATTORNEYS.

UNITED STATES PATENT OFFICE.

WILLIAM MANDEL, OF MINNEAPOLIS, MINNESOTA.

STORM-SASH FASTENER.

1,421,798.

Specification of Letters Patent.

Patented July 4, 1922.

Application filed February 5, 1921. Serial No. 442,803.

To all whom it may concern:

Be it known that I, WILLIAM MANDEL, a citizen of the United States, residing at Minneapolis, in the county of Hennepin and State of Minnesota, have invented certain new and useful Improvements in Storm-Sash Fasteners, of which the following is a specification.

My invention relates to storm sash fasteners, and an object is to provide a device of this kind which when attached to the middle of the lower storm sash member, may be employed to hold this sash in either open or closed position as may be desired. Another object is to provide a fastener which is retained on the storm sash when stored so that the fastener can neither become lost nor break the glass in the sash.

The full objects and advantages of my invention will appear in connection with the detailed description thereof, and the novel features embodied in my inventive idea will be particularly pointed out in the claims.

In the accompanying drawings which illustrate the application of my invention in one form,—

Fig. 1 is a vertical sectional view showing the ordinary window sash in position in the window frame, and the storm sash held in open position by my fastener. Fig. 2 is a detail view showing the fastener as it appears when looking downwardly thereon or at right angles to the position shown in Fig. 1. Fig. 3 is a detail view showing an eye member secured to the lower member of the storm sash. Fig. 4 is a detail plan view showing the lower frame member of the storm sash in horizontal section and showing the fastener in the position which it occupies when the storm sash is in its closed position. Fig. 5 is a detail view showing the lower storm sash member in section and showing the fastener in the position in which it is placed when the sash is to be stored.

Referring to the particular construction shown in the drawings, the numeral 10 designates a small plate which is secured to the middle of the window sill S by screws 12, this plate having an upstanding pin 14 which preferably extends out from the plate at a slight angle to a right angular position so that this pin will be in vertical position when the plate is secured to the inclined surface of the sill. The lower member L of the storm sash is provided at its middle with

an eye member 16 secured thereto by screws 18. A rod 20 extends slidably through the eye member 16. The outer portion of the rod 20 is curved at 22 and is provided with a head 24 at its end which prevents the rod sliding entirely out of the eye member. When the storm sash is pivotally attached at its upper end to the window frame in the usual manner, said sash may be held in open position as shown in Figs. 1 and 2 by passing the looped inner end 26 of the rod 20 over the pin 14. In this position, the middle of the curved member 22 is in the eye member 16 as shown in Fig. 2. When it is desired to close the storm sash, the loop 26 is removed from the pin 14 whereupon the sash swings inwardly and may be held in closed position by sliding the rod 20 through the eye member so that the head 24 comes into engagement with this member. This causes the rod 20 to extend at right angles to its former position and it then engages the pin 14, as shown in Fig. 4 so that the curved portion 22 in cooperation with the pin 14 holds the sash firmly in position and prevents rattling. The rod 20 is provided with a slight bend 28 between its ends. When the sash is removed for storing, the rod 20 is slid until the bend 28 lies in the eye member 16 and the rod is then turned over so that it occupies the position shown in Fig. 5. The rod on account of its resiliency is held in this position, and danger of its pressing on the glass and breaking the same is avoided.

The advantages of my invention will be readily understood from the foregoing description. The fastener may be readily attached and a single one serves to hold the sash in either open or closed position, since the fastener is attached at the middle of the sash. My fastener is, therefore, cheaper than fasteners which are attached to the sides of the sash in which case two fasteners are required to hold the sash firmly. The fastener cannot become lost, and when placed in proper position for storage of the sash, it is held so that it cannot press upon the glass with liability of breaking the same.

I claim:

1. A storm sash fastener comprising a rod having a curved outer portion, an eye member adapted to be secured to the middle of the lower sash member, said curved portion extending slidably through said eye

member, a pin adapted to be secured to the middle of the window sill, and a looped portion on the inner end of said rod for engagement with said pin for holding the sash in open position, said pin being also adapted for engagement by said curved portion for holding the sash in closed position.

2. A storm sash fastener comprising a rod, an eye member adapted to be secured to the middle of the lower sash member for slidably receiving said rod, an engageable

member adapted to be secured to the middle of the window sill, and means on the inner end of said rod for engagement with said engageable member for holding the sash in open position, said rod having a bend between its ends which is adapted to engage said eye member and hold said rod firmly upon said lower sash member when the sash is stored. 15

In testimony whereof, I hereunto affix my signature.

WILLIAM MANDEL.
